UNITED STATES PATENT OFFICE.

JOSEPH W. HORTON, OF BLOOMFIELD, NEW JERSEY, ASSIGNOR TO WESTERN ELECTRIC COMPANY, INCORPORATED, OF NEW YORK, N. Y., A CORPORATION OF NEW YORK.

WAVE MODULATION.

Application filed January 4, 1924. Serial No. 684,305.

The present invention relates to wave control and has particular application to signaling and similar systems in which waves to be transmitted are modified by signal 5 variations or the like.

It is an object of the invention to effect wave control or modulation in a simple and efficient manner.

A feature of the invention comprises the 10 use of a condenser to effect wave modulation by capacity variations.

A related feature comprises a condenser of special type for obtaining the desired 15 character of wave to be modulated.

16 Briefly and specifically, the invention makes use of the principle that in any circuit having capacity, the current in the circuit is a function of the capacity and its wave form can be principally determined by 20 the capacity variations if the other constants of the circuit remain substantially the same. In the circuit according to the invention the constants are preferably such that the circuit is non-resonant or aperiodic.

25 The capacity may be embodied in a suitable type of condenser which is variable either at the frequency of the wave to be modulated or of the modulating or control wave. If a source of potential variations 30 is connected into the circuit, the condenser offers a varying impedance to the flow of current in the circuit, the impedance variations being in accordance with the wave 35 variations used to control the condenser.

35 The various objects and features of the invention will appear more fully from the following detailed description of certain embodiments disclosed in the accompanying drawing.

40 Fig. 1 is a schematic representation of a modulating circuit according to the invention, in which the capacity is varied at the carrier frequency;

45 Fig. 2 is a similar representation of a circuit employing a different type of condenser;

Fig. 3 gives curves illustrative of the design of the condenser employed in Fig. 2; and

50 Fig. 4 shows a circuit in which a capacity is varied at speech frequencies to modulate a carrier wave.

Referring first to Fig. 1, the condenser

illustrated in this figure is shown as comprising a stationary plate 1 and a movable plate 2. The movable plate is in this figure 55 in the form of a vibrating bar of diaphragm mounted on suitable fulcrums or bearing points 3 and 4. As shown, the bar is supported for free flexural vibration, the fulcrums being substantially at the fundamental nodes, which, as is known, should be located at points 0.22418 of the length of the bar from its ends. A magnet 5 may be employed for maintaining the bar in a state of vibration, this magnet being energized from any suitable source 6 of waves of the frequency to be modulated. This source may be a separate unit such as a vacuum tube oscillator, or the magnet 5 may have a winding supplied with driving energy from the output of amplifier A so that the system including magnet 5, condenser 1, 2 and tube A 60 form a regenerative circuit.

The condenser 1, 2 is connected in circuit with the secondary 7 of a speech transformer, and preferably a vacuum tube amplifier A. The output of the amplifier may be connected to any suitable load circuit L.

Speech currents from the microphone circuit 8 set up potential variations across the terminals of the secondary 7. These potential variations energize the series circuit including the condenser 1, 2 and the input circuit of the amplifier A. This input circuit is shown as comprising the resistances 10 and 11 shunted by the grid-filament impedance of the tube, this latter being generally of such high order that it may be considered practically an open circuit. The battery 12 may be inserted for polarizing the grid and the blocking condenser 13 may be made sufficiently large to offer negligible impedance in the series circuit.

The potential variations in the coil 7 set up current flow in the closed circuit, as above traced, including the condenser 1, 2 and the resistance in shunt of the grid and filament of the tube A. This current charges the condenser 1, 2, and if the resistances 10 and 11 and the frequency of vibration of the bar 2 have such values that the charge on the condenser does not leak off immediately but persists for a few periods of vibration of the bar 2, there will be a high 100 105

frequency voltage set up across the terminals of the condenser 1, 2. If the potential across the terminals of coil 7 were constant, there would be a voltage wave developed between the terminals of condenser 1, 2 having a frequency equal to the frequency of vibration of the bar 2 and having a constant maximum amplitude. Since the voltage variations in coil 7 are variable, the voltage wave developed in the condenser 1, 2 is a modulated wave having a variable amplitude, depending upon the instantaneous amplitude of the voltage generated in the coil 7. The voltage variations from the condenser 1, 2 are impressed across the terminals of resistance 10 and produce variations in the potential of the grid of the tube A with respect to its filament. Due to the well known action of the device A, amplified waves of the same form as those impressed on the grid are transmitted into the load circuit L.

By closing the switch 14 an additional capacity 15 may be included in parallel with the condenser 1, 2 to increase the total capacity of the circuit. When the condenser 15 is in circuit, the percentage change in capacity produced by a given variation in the capacity of the condenser 1, 2 is smaller than when the condenser 15 is omitted. The degree of modulation produced may therefore be controlled by the amount of capacity included in parallel with the condenser 1, 2.

In Fig. 2, the portion of the system to the right of the broken vertical line may be considered identical to that shown in Fig. 1 to the right of the corresponding broken line. In Fig. 2, a somewhat different type of variable condenser is shown from that of Fig. 1. This condenser includes one or more fixed plates 16 and one or more rotatable plates 17 mounted on the shaft 18 and arranged to be continuously rotated by means of the motor 19.

The condenser 16, 17 is preferably constructed so that by rotating the plate 17 at a constant speed with respect to the plate 16, sinusoidal variations in capacity are produced. This may be accomplished by using a plate 16 having a straight edge which passes through the axis of the shaft 18, and by fashioning the plate 17 in the manner more fully indicated in Fig. 3.

In this figure the dotted line is a circle of radius r and is defined in polar coordinates as

$$R = \sin \Theta$$

The shape to be given to the plate 17 is indicated in Fig. 3 by the solid curved line 20, and its contour is defined by the equation

$$R^2 = \sin \Theta$$

where r has the same value as in the previous equation. If a plate of this shape is mounted on the shaft 18 so that the origin in Fig. 3 coincides with the axis of the shaft, then

when the plate is rotated the capacity of the condenser 16, 17 varies sinusoidally according to the relation

$$C = \bar{C}(1 + \cos \theta)$$

where C represents the instantaneous capacity and $\bar{C}$ is the average capacity, θ being equal to the frequency of rotation multiplied by 2π . A condenser of this type has the advantage not only of producing sinusoidal voltage variations, but of permitting large changes in the capacity since any desired size may be given to the plates, and also a condenser may be built up from a number of plates as in the case of the usual variable air condenser. It will be understood that the operation of the circuit of Fig. 2 is essentially the same as that indicated in Fig. 1. The movable plate 17 is rotated at the carrier frequency, and when speech currents are set up in the circuit 8, a wave of the carrier frequency modulated by speech is produced and transmitted.

In Fig. 4, the variable condenser is controlled by speech waves and in turn controls the amplitude of carrier waves impressed on the circuit from a carrier frequency source. The carrier source is indicated at 21 and may be of any suitable type, such as a vacuum tube oscillator. The carrier waves may be amplified by the vacuum tube amplifier A' and the resulting amplified waves impressed on the modulating circuit through the transformer 22. When speech is directed against the diaphragm 23, which forms the movable plate of the condenser 23, 24, the impedance of the series circuit including the secondary of transformer 22, the condenser 23, 24 and the primary of the output transformer 25, is varied in accordance with speech variations so that a variable amplitude wave results. The modulated wave is then transmitted to the load circuit through the filter F, suitable amplification being also supplied if desired.

The series circuit including the variable condenser in each of the figures is preferably substantially aperiodic so that the modulating action is carried out independently of any resonance effects and depends principally upon the capacity reactance of the variable condenser.

Instead of producing the capacity variations as in each of the figures by moving one of the plates of a condenser, these variations may be effected by moving a dielectric. For example in Fig. 2, the number 17 may be of dielectric material, rotatable between a pair of condenser plates 16 connected in the circuit. Also in Figs. 1 and 4 the vibrating member may be of dielectric material positioned between the condenser plates.

Various other modifications of the modulating systems illustrated in the drawing will occur to those skilled in the art, the

scope of the invention being defined in the following claims.

What is claimed is:

1. In a modulating system, a substantially aperiodic circuit, means for causing a flow of current therein responsive to a variable voltage impressed thereon from a source external to said circuit, a variable capacity in said aperiodic circuit, and means to control said capacity in accordance with wave variations to be transmitted.
2. In a modulating system, a substantially aperiodic circuit, means for causing a flow of current therein responsive to a variable voltage impressed thereon from a source external to said circuit, a variable capacity in said aperiodic circuit, and means to control said capacity in accordance with wave variations whereby a variable amplitude wave is produced, the amplitude of said wave being substantially independent of any resonant effect in said circuit.
3. In a transmitting system, a circuit, a source of signal voltage variations therein, a condenser in series with said source, and means for varying the capacity of said condenser at the carrier wave frequency to produce a signal-modulated wave.
4. In a transmission circuit, a condenser having one plate movable with respect to another plate, means to move the movable
5. In a modulating system, a vacuum tube having a cathode, a grid and an output electrode, a resistance connected across the grid and cathode, a source of signaling voltage variations and a variable condenser in series with each other and said resistance, means to vary the capacity of said condenser at the carrier wave frequency whereby a modulated wave is produced, and an outgoing circuit coupled to said output electrode.
6. In a modulator circuit including an electric discharge tube having a cathode, and a grid or the equivalent; a series circuit including said grid and cathode, a source of signaling potential variations, and a capacity; and means to vary said capacity at the carrier wave frequency to produce a signal-modulated wave.
7. A modulator circuit as claimed in claim 6, said capacity and the means for varying the same being of a type to produce sinusoidal variations in capacity.

In witness whereof, I hereunto subscribe my name this 3 day of January, A. D., 1924.

JOSEPH W. HORTON.
